UNITED STATES PATENT OFFICE.

MALCOLM G. EWER, OF DETROIT, MICHIGAN.

PIPE-WRENCH.

No. 833,516.

Specification of Letters Patent.

Patented Oct. 16, 1906.

Application filed August 23, 1905. Serial No. 275,343.

To all whom it may concern:

Be it known that I, MALCOLM G. EWER, a citizen of the United States, residing at Detroit, county of Wayne, State of Michigan, have invented a certain new and useful Improvement in Pipe-Wrenches; and I declare the following to be a full, clear, and exact description of the invention, such as will enable others skilled in the art to which it pertains to make and use the same, reference being had to the accompanying drawing, which forms a part of this specification.

This invention relates to pipe-wrenches.

It has for its object an improved quick-adjustment pipe-wrench.

In the drawing the figure shows the fixed jaw in elevation and the sliding jaw in section.

1 indicates the fixed jaw with a tang or 20 handle 2, provided with a screw-threaded cut rack 3. The sliding jaw 4 engages over the tang 2, which projects through openings 5 and 6 in the back of the sliding jaw 4. Of these the opening 6 is very slightly larger 25 than the tang, and the opening 5 is considerably larger than the tang, so that the forward end 41 of the sliding jaw can rock slightly on the point 7 as a pivot, to which it is held by the face 8. The rocking movement 30 is limited by the extent of the opening 5.

At the front end of the sliding jaw 4 is a bit 9, the rear face of which is curved and engages with a curved face 10 at the front of the sliding jaw, the face 10, however, being 35 at the bottom of a recess within which the bit 9 is received. The bit 9 is held from escaping from the recess by pin 11, that engages through a curved slot 12 in the bit. The sliding jaw is held adjustably in place by a 40 pivoted and swiveled screw 13, the front end of which is pivoted to the rear of the jaw 4 in a recess or cavity into which pivot-knuckle 17 at the front of the screw extends. On that side of the screw which is opposite the 45 tang 2 is a concealed spring 14, that bears against a shoulder 15 on the knuckle of the screw and normally tends to hold the screw in engagement with the rack 3. The threads of the screw are broad and are knurled or milled 50 to afford a sufficient grip for the fingers to turn the screw. The screw itself is swiveled to the pivot-knuckle 17 and is readily revolvable to drive the sliding jaw along the tang.

The knuckle 17 engages in a cavity at the 55 rear of the jaw 4 and is itself provided with a seat for the reception of the neck 18 of the

screw. The periphery of the knuckle 17, or at least that part of the periphery of the knuckle 17 which lies immediately adjacent to the tang, is curved and engages between 60 the pivot 16 and the tang with a bearing engagement against the tang. The knuckle closely confines the tang between itself and the point 7 of the strap, by which this part of the sliding jaw is held to the tang. Preferably 65 the point 7 is produced by thickening the strap slightly at the middle, producing a slight clearance at each side of the point between the strap and the tang 2. When the screw is in position to drive the jaw, the 70 knuckle bears against the tang, holding the tang between itself and the point 7, which lies directly across from the bearing-point of the knuckle. The neck 18 of the screw engages in the seat 19 and is provided with an 75 annular groove 20, in which engages a short holding-screw 21, which allows the screw 13 to turn in its bearings independent of the knuckle 17, whereas it swings on the pin 16 with the knuckle 17. 80

In action when the jaws are engaged over a pipe the sliding bit 9 assumes a position somewhat more nearly parallel to the bit 92 than that shown in the drawing and holds tenaciously on the pipe so long as the proper 85 twisting motion for turning the pipe is continued or so long as pressure toward such turning motion is continued. As soon, however, as the reverse pressure is given to the wrench the sliding jaw rocks to bring the 90 back 51 into engagement with the tang and loosens the hold of the jaw on the pipe. The rack part with which the screw engages is located on the tang beyond the place where a pipe can touch it under any ordinary circumstances and is not liable to be marred by 95 the use of the tool.

What I claim is—

1. In a pipe-wrench, in combination with a fixed jaw and a tang therefor, a sliding jaw 100 provided with an embracing band at one end thereof adapted to engage against the back of the tang and with a pivoted knuckle having a curved bearing-surface engaging the tang opposite thereto, an adjusting-screw 105 swiveled on said pivoted knuckle, an embracing band at the gripping end of said jaw loosely surrounding the tang whereby there is freedom of rocking movement of the jaw with respect to the tang, substantially as 110 described.

2. In a pipe-wrench, in combination with

a fixed jaw and a tang therefor provided with a screw-threaded cut rack, a screw engaging said rack, pivotal connections between the screw and the jaw, a curved bearing interposed between the pivot and the tang and engaging against said tang, a band secured to the jaw and embracing the tang and provided with an engaging face engaging the tang opposite the bearing on said pivot, a second band distanced from the first and near the gripping end of the jaw, the said second band engaging with clearance around the band, substantially as described.

3. In a pipe-wrench, in combination with a fixed jaw and a tang therefor provided with a screw-threaded cut rack, a screw engaging said rack, pivotal connections be-

tween the screw and the jaw, a bearing engaging around the pivot and against the tang, a band secured to the jaw and embracing the tang and provided with a curved engaging face opposite the said interposed bearing, a second band distanced from the first and near the gripping end of said jaw, the second band engaging with clearance around the tang, and a movable bit forming the gripping part of said jaw, substantially as described. 20 25

In testimony whereof I sign this specification in the presence of two witnesses.

MALCOLM G. EWER.
